UNITED STATES PATENT OFFICE.

JOHN DISTELHORST, OF BURLINGTON, IOWA, ASSIGNOR TO ADOLPH H. RICHTER, OF SAME PLACE.

GRATING AND SLICING DEVICE.

SPECIFICATION forming part of Letters Patent No. 394,759, dated December 18, 1888.

Application filed May 7, 1888. Serial No. 273,157. (No model.)

To all whom it may concern:

Be it known that I, JOHN DISTELHORST, a citizen of the United States of America, and a resident of Burlington, in the county of Des Moines, State of Iowa, have invented certain new and useful Improvements in Grating and Slicing Devices, of which the following is a specification.

This invention relates to means for comminuting horse-radish, nutmegs, roots, and the like, and also for the slicing or cutting into small pieces of potatoes and other vegetables.

The object of the invention is to produce a device for the purposes in question which may be manufactured at small cost and efficiently perform the work intended, and which may be organized for family use and the retail drug trade, and also be capable of being built of such proportions as to render it available for the use of spice and root grinding establishments.

The invention is hereinafter described, and its novel features, for which protection by Letters Patent is desired, are specified in the claims at the end of this specification.

In the accompanying drawings, which form part of this specification, and in which like features are indicated by like figures of reference in the several views, Figure 1 is a view in elevation of the hopper side of a device embodying my improvements. Fig. 1^a is a fragment of the grinding or cutting plate, showing the manner of forming the grinding or cutting perforations of Figs. 1 and 4. Fig. 2 is a top view looking down on the hopper, grinding-plate, &c. Fig. 2^a is a cross-section through line x x of Fig. 2. Fig. 3 is a detached view of the grinding-plate shown in Fig. 1, illustrating the arrangement of the perforations. Fig. 4 is a plan view of a modification of the cutting-plate. Fig. 5 is a cross-section through line y y of Fig. 4, and Figs. 6 and 7 are illustrations of modifications of the manner of forming the perforations of the grinding or cutting plate.

Referring to the drawings, 9 indicates the support for the grinding or cutting disk, the said support being of metal and having at its lower end the screw-clamp 10, by means of which the device may be conveniently secured to a bench or table. At the upper end of support 9 there is provided a shaft-bear-

ing, 11, and extending therefrom and preferably integral therewith is the hopper-supporting piece 12, the edge 13 of which serves as a 55 scraper, in the manner hereinafter explained. The hopper 14 is fixed to its supporting-piece 12 in any suitable manner that will permit the providing of a space between the same and the scraper-edge 13, within which space 60 the grinding or cutting plate 15 rotates.

As shown, the standard 9, hopper-supporting piece 12, and hopper 14 are formed integral; but they may be made separately and be secured to one another in proper relative 65 position by any suitable means. The edge 13 of hopper-supporting piece 12 is arranged a slight distance below the adjacent or inner top surface of hopper 14, as shown in dotted lines, Fig. 1, and in Fig. 2^a, and the hopper 70 itself, preferably, inclines somewhat toward the cutting-disk, so that instead of forming a right angle therewith the angle of approximate juncture is more or less acute, as shown in Fig. 2^a.

The grater or cutter 15 is made of tin, steel, or sheet-iron, and is, by preference, of circular form, and it is supported in appropriate relation to the hopper 14 and scraper 13 upon shaft 18, which is supported in bearing 11, as 75 shown.

The form and arrangement of the cutting or grating perforations 23 of plate 15 are such that they will not clog up, and the grated material will not be scattered as it is discharged 85 at the back of said plate, but will be delivered in a heap. The perforations 23 are all punched out on the same side, so that one side of the plate—the rear side or that with which the scraper-edge 13 of the hopper-supporting piece co-operates—is smooth, the cutting or grating edges of the perforations all being on the hopper side of the plate. The perforations 23 are arranged, for example, as shown in Fig. 3, and the cutting-edges 24 of 90 the same are (in the act of punching out the metal) struck up uniformly, so that as the plate is rotated in the proper direction they will all be presented to the material to be 95 grated or cut. The cutting-edge of each perforation comprises about one-half of its circumference, as shown in Fig. 1^a, and is formed by raising the metal at the back of the perforation. This arrangement of the perfora-

tions and their cutting-edges facilitates the passage of the grated material through the perforations.

In Fig. 6 the perforations 23 are formed with 5 teeth occupying about one-half of the circumference of each perforation, and in Fig. 7 the perforations 23 are cone-shaped with the cutting-edges 24 formed by raising the metal above the plane of the disk. This last-men- 10 tioned construction cuts the substance acted upon into a stringy condition. In Fig. 4 there is shown a construction of cutting-disk specially adapted for slicing potatoes and other vegetables and fruits. The plate is divided 15 into three parts. The cutting-edges 24 are slightly raised above the surface of the adjacent disk-sections and are sharpened, so that by revolving the disk in the proper direction, as indicated by the arrow, the pota- 20 toes or the like are sliced in pieces of uniform thickness.

It is of course to be understood than any of the forms of cutting or grating plates illustrated may be employed, and the substitution of 25 one form of cutting or grating plate for another is readily accomplished by removing the crank 21.

In using my device the substance to be 30 grated or cut is placed in hopper 14 and held in contact with the plate 15 by the hand, or by any suitable mechanism. As the said disk is revolved the cutting-edges of the perforations 23 repeatedly come in contact with the substance to be comminuted, thus cutting or 35 slicing the same, as the case may be, in the manner already explained. The comminuted or sliced material as it passes through the perforations or slits of the plate 15 is scraped off said plate by the edge 13 of the hopper- 40 supporting piece, which, as explained, occu-

pies a position just below the top surface of the inner end of hopper 14. As the grated substance is scraped off, it falls into a receptacle arranged beneath the apparatus, and is not thrown out from the disk and scattered, 45 the inclination of the hopper-supporting piece 12 and its beveled surface contributing toward the accomplishment of this result.

Having thus described my invention, what I claim as new, and desire to secure by Letters 50 Patent, is—

1. In a device of the character herein described, a support provided with a laterally-extended arm, in combination with a revolving cutting-plate, the said arm on one side of 55 said cutting-plate forming a scraper and on the other side a hopper-support, substantially as set forth.

2. The support 9, provided with a shaft-bearing and a laterally-extended scraper, in 60 combination with a hopper supported on said laterally-extended scraper in such manner as to form an acute angle of approximate juncture therewith and to provide an unobstructed space between scraper and hopper, and a cutting-plate mounted to revolve vertically between the hopper and scraper, substantially 65 as set forth.

3. The support 9, provided with screw-clamp 10, shaft-bearing 11, and combined 70 hopper-supporting piece and scraper 12 13, in combination with hopper 14, cutting-plate 15, and shaft 18, the cutting-plate secured to shaft 18 and arranged to revolve vertically between the hopper and scraper, substantially 75 as set forth.

JOHN DISTELHORST.
